ABSTRACT OF THE DISCLOSURE

Photographic film processing apparatus comprising a fluid applicator and a barrier support. The fluid applicator applies a uniform layer of fluid to the film at speeds in the neighborhood of 100 feet per minute. The barrier is provided with smooth walls parallel to the film path and extending into the applicator.

BACKGROUND OF INVENTION

Field of the invention

This invention falls in the class of machines and certain generally related articles and processes for the fluid treatment of strip material. A preferred embodiment of this invention falls in the class of machines, articles and processes for the production of pictures by the fluid treatment of photographic film containing a latent image, which latent image was obtained by the action of activating radiation, electron beams, and the like upon a medium sensitive to the same.

Description of the prior art and objects

Present systems for the rapid processing of photographic film are subject to a number of difficulties. These difficulties are especially great in high speed automatic film processing equipment used to process film for data storage on film, microfilming and aerial photography. In such applications there may be as many as one hundred lines per millimeter of film. Any uneven development of the film can result in serious error when the film is recovered and printed out. In the processing of aerial photographs, for example, development must be as even as possible since subtleties of light and shade play a very important part in subsequent interpretation of these photographs. Displacement of the emulsion gel may also cause serious difficulties since uneven refraction of light passing through the gel can cause distortion of the recorded image. Serious errors when the information on the film is printed out can thus occur. For any application requiring a high degree of accuracy such errors must be avoided. A further problem of prior art film processing equipment is the abrasion caused to the film in the passage of the film over a plate, roller, or other surface. Even a minor scratch or blur may be critical where high accuracy of the recorded information is required. For example, to obtain the high speed desired in processing equipment it is often necessary to apply a large plurality of upper and lower rollers through which the vertically oriented film passes. To obtain these speeds it may be necessary to employ up to 240 rollers. The accumulation of sediment on the roller surface and/or uneven alignment of the rollers may cause abrasion and/or uneven development of the film surfaces. On the other hand, processing equipment such as described in U.S. Patent No. 3,192,846, while eliminating a number of rollers needed for film processing also may cause uneven film development and/or displacement of the gel surface due to uneven fluid flow and/or uneven turbulence of the fluid. In attempting to overcome these difficulties when operating at high speeds, e.g., at speeds up to 100 feet per minute, large

2

amounts of fluid have been employed. However, when large amounts of fluid are used in the process fluid turbulence is lost at the film surface thereby resulting in inferior development and final prints of inferior quality. In addition large pumps are required thereby undesirably increasing the size and cost of the processing equipment.

SUMMARY OF THE INVENTION

In accordance with one embodiment of the invention a pair of liquid applicators dispense very thin sheets of processing fluid into a narrow channel which contains the moving film to be processed. The liquid is initially applied as thin sheets to the upper and lower film surfaces at a small angle of attack with respect to the surfaces to prevent uneven overall turbulence which may cause destructive film flutter or resonance. The use of a narrow channel enables the employment of surprisingly small quantities of fluid which reduces the sizes of the recirculation pumps, while the use of liquid applicators having uniform cross sections along the width of the film together with the narrow channel provide for pressure and development uniformity. The fluid dispensing nozzle and the channel forming barrier means may be in part formed of a unitary structure to eliminate undesirable rough edges which could result in film abrasion and turbulence producing components.

The principal object of the present invention is to provide a new and improved film processor. A further object of this invention is to provide a high speed film processing apparatus which provides for effective agitation of the processing fluid at the film surface.

Another object of this invention is to provide a film processing apparatus of the above character which applies processing fluid to a film with a minimum of displacement of the film in emulsion.

Another object of this invention is to provide a high speed film processing apparatus of the above character in which the dangers of damage to film during processing are at a minimum.

Another object of this invention is to provide a film processing apparatus which operates at very high speed and yet requires a surprisingly small quantity of processing fluid.

Another object of this invention is to provide a film processing method and apparatus of the above character in which the film is supported by a uniform fluid bearing layer of processing fluid as the film goes through the processing stage.

Another object of this invention is to provide a film processing method and apparatus of the above character in which the film is supported by a uniform fluid bearing layer of processing fluid as the film goes through the processing stage.

Another object of this invention is to provide systems, methods, and apparatus for the high speed processing of film in which relative movement between the film and a thin layer of processing fluid creates uniform turbulence in the field adjacent to the film, and prevents overall uneven turbulence which causes destructive film flutter.

Another object of this invention is to provide systems, methods, and apparatus for the fluid treatment of film in which the film is developed at a high degree of uniformity and accuracy.

Another object of this invention is to provide systems, methods, and apparatus for processing photographic film in which processing time has been substantially reduced.

Another object is to obtain greater control of maximum density and contrast for a given temperature of developer solution.

Another object of this invention is to provide a method for continuously processing strip photographic film.

Another object of this invention is to provide systems, methods, and apparatus of the above character which are inexpensive and reliable in operation.

These and other objects will be apparent from the disclosure which follows:

BRIEF DESCRIPTION OF THE DRAWINGS

A better understanding of this invention and its many advantages will be had by referring to the accompanying drawings, in which

FIGURE 1 is a perspective, schematic view of one embodiment of the invention;

FIGURE 2 is a cross-sectional, schematic view of the processing chamber taken along lines 2—2 of FIGURE 1; and

FIGURE 3 is a view of a smooth surface which forms part of the barrier means and fluid applicator means of FIGURES 1 and 2.

DESCRIPTION OF THE PREFERRED EMBODIMENTS

In accordance with this invention a continuous moving film is processed by a data processing apparatus comprising a fluid applicator and a barrier means. The fluid applicator delivers a thin fluid layer of fluid having uniform pressure across the surface of the continuous moving film. The angle of incidence of the film layer with respect to the film is maintained at less than about 45 degrees and is preferable from about 15 degrees to about 25 degrees such that the film layer possessing substantially uniform turbulence within given laminas to provide overall laminar flow between the barrier means and the film wherein substantially none of the emulsion gel of the film is displaced. The fluid layer is applied to the film as a uniform layer across the film. The fluid layer has a width of up to about $\frac{1}{16}$ inch and preferably about $\frac{1}{32}$ inch. However, the width of this fluid layer may be varied somewhat depending upon the viscosity and composition of the fluid layer velocity of the fluid layer and the coefficient of friction of the barrier means and the film with respect to the fluid layer. The fluid applicator is preferably joined to the barrier means. For example, in certain applications it may be desirable to utilize a barrier means composed of a fluid having a viscosity substantially different than the viscosity of the processing fluid. On the other hand, certain embodiments of this invention may comprise barrier means such as in the form of a moving belt. The barrier means is a noncompressible composition and/or structure spaced at a distance from the film, such distance being substantially the same as the width of the fluid layer which is applied by the fluid applicator to the film. The barrier means helps to maintain a fluid layer across the film having a uniform flow rate and uniform width and pressure. The coefficient of friction of the barrier means with respect to the fluid layer can be varied depending upon the viscosity of the fluid layer, speed of the fluid layer, nature of the film being processed, and like factors known to one skilled in the art. For example, a material having a low coefficient of friction such as polytetrafluoroethylene may be used when extremely high speed film processing, such as 100 feet per minute is desired. In such a process the fluid layer may preferably be less than about $\frac{1}{64}$ of an inch in width.

A preferred embodiment of this invention involves using pairs of the film processing units of this invention on both sides of the film, each unit being spaced at substantially equal distances from the film and in such a position that the pressure on one side is substantially balanced by the pressure on the other side of the film. In this manner both sides of the film can be processed in one step. On the other hand, where it is desired to process only one side of the film it may be desirable to utilize the apparatus of this invention on only one side of the film and to utilize roller bearings, air bearings or other support means known to the art on the other side of the film. A series of paired data processing units may be combined to

form a complete data processing system utilizing one or a series of different fluids for processing of film.

It is understood that the data processing system of this invention may be utilized in series to form a film path through which film can be processed.

FIGURES 1 and 2 show a preferred embodiment of this invention wherein the fluid applicators 11, 21 and barrier means 12, 22 form unitary film processing apparatus (or units) 10, 20 and comprise fluid inlet gaps 13, 23. The film, 3, passes between the pair of film data processing units 10, and 20 in a plane substantially parallel to the planes formed by the planes of the barrier means on each side of the film. The smooth surface, 30, of FIGURE 3 is an amplified view of 17 and 27, and acts as a barrier means for maintaining the uniform fluid flow between the film and said smooth surface, a means of distributing a uniform fluid pressure to the fluid distributing chambers, 14, 24 and from the fluid inlet chambers, 15, 25 and provides a smooth joinder of the fluid applicator and the barrier means thereby eliminating rough edges which cause undue turbulence and abrasion of film surfaces. The apertures 31, may be adjusted in size and position to obtain the desired uniform pressure in the fluid distributing chambers. The smooth surfaces 17, 27 are preferably bonded to the other part of the barrier means, 12, 22 by means of adhesive, screws, such as 18, bolts, or the like. The screws 19 are used to join the back of the applicators to the applicators thereby forming the fluid distributing chambers 14, 24. Thus the fluid applicator of the preferred embodiment of FIGURES 1 and 2 may be readily disassembled for cleaning, repairs, maintenance, etc.

The applicators may be arranged so that the direction of the flow of fluid is in any direction in relation to the direction which the film is passing so long as the fluid forms a film of uniform turbulence and thickness between the barrier means and the film. It is however, preferred that the fluid flows in the direction in which the film is traveling since the fluid serves the additional function of propelling the film through the developer system thereby eliminating the need of rollers or other type of propelling means. Such a system also has the advantage of being self-threading, i.e., the film does not have to be hand threaded through the data processing system of this invention. The high speed data processing system of this invention may, of course, be provided with stations for reversing the direction of the film flow to form a number of tiers of tandemly mounted data processing units, thereby enabling the data processing system to be stored in a very compact amount of space. The fluid applicator may be of varying width and shapes depending upon the width, shape, and direction of flow of film being processed. For example, a cylindrical shape film would use a cylindrical shaped fluid applicator and barrier means. The barrier means of the data processing apparatus of this invention can also be curved in order to change the direction of the flow of the film.

A preferred embodiment of the fluid applicator means of this invention wherein a fluid layer possessing substantially uniform turbulence and substantially uniform laminar flow is applied to a continuous moving film comprises (a) an inlet fluid holding chamber 15, 25 of FIGURE 2, wherein the fluid pressure is built up and provided with means for controllably allowing the fluid to pass to a (b) fluid distributing chamber 14, 24 of FIGURE 2, which is provided with a uniform outlet aperture for allowing a fluid layer to pass into the space between the barrier means and the film path.

This invention provides a high speed data processing apparatus which maintains a uniform fluid bearing layer of processing fluid for supporting a continuous moving film which is going through the process stage. This film processing apparatus provides for effective agitation of the processing fluid at the film surface with a uniform turbulence, therefore, it is now possible to process film

at very high speeds, up to about 100 feet per minute, and obtain as a final product developed film and prints of very high quality.

It will be understood that this invention can also be applied for processing strip material other than photographic film in the strict sense. For example, data storage tapes wherein the information has been recorded magnetically, by pressure tracing or by a like process may be treated with the apparatus of this invention.

Therefore, it can be seen that this invention is applicable to any type tape or material where it is desired to apply a fluid layer having uniform turbulence and uniform laminar flow across said tape.

While there have been described above what are presently believed to be the preferred forms of the invention, variations thereof will be obvious to those skilled in the art. All such changes and variations which fall within the spirit of the invention are intended to be covered by the generic terms in the appended claims, which are variably worded to that end.

What is claimed is:

1. In a high speed processing apparatus comprising (1) a fluid applicator means for applying a substantially uniform processing fluid layer to a continuous moving film and (2) a barrier means which acts as a support for maintaining said fluid layer against the film, the improvement comprising providing said fluid applicator means with a means for applying a thin fluid layer having a width up to $\frac{1}{16}$ inch of substantially uniform width and pressure to the film at an angle of incidence of the thin fluid layer across the film of less than about 45 degrees and wherein the barrier means comprises smooth walls substantially parallel to the film path and extending for a substantial distance along the film path and into the applicator means and wherein the processing apparatus comprises means for moving said fluid at high speeds in the neighborhood of 100 feet per minute and wherein the barrier means is adjacent to the film in order to maintain a thin fluid layer between the film and barrier means in order to maintain a fluid layer possessing substantially uniform turbulence and substantially uniform overall laminar flow between said barrier means and said film.

2. In a high speed data processing apparatus comprising (1) a liquid applicator for applying a processing uniform liquid layer against the film, the improvement comprising providing said liquid applicator with a means for applying a thin liquid layer of substantially uniform width and pressure across the film at an angle of incidence of the thin liquid layer to the film of less than about 45 degrees and wherein the processing apparatus comprises means for moving said fluid at high speeds in the neighborhood of 100 feet per minute and a barrier means adjacent to the film for maintaining a thin liquid layer having a width up to $\frac{1}{16}$ inch against the film in order to maintain a liquid layer possessing substantially uniform turbulence and substantially overall uniform laminar flow between said barrier means and said film and wherein the barrier means comprises smooth walls substantially parallel to the film path and extending for a substantial distance along the film path and into the applicator means.

3. A high speed data processing apparatus as in claim 2 wherein said liquid applicator comprises (a) an inlet liquid holding chamber wherein the liquid pressure is built up and provided with means for controllably allowing the fluid to pass to a (b) liquid distributing chamber which is provided with a uniform thin outlet aperture, for allowing the liquid layer to pass into the space between the barrier means and the film.

4. A high speed data processing apparatus as in claim 3 wherein said thin outlet aperture has a width of less than $\frac{1}{16}$ inch.

5. A high speed data processing apparatus as in claim

2 wherein said liquid applicator has a thin outlet aperture for applying the liquid layer to the film.

6. A high speed data processing apparatus as in claim 2 wherein the liquid applicator is oriented to apply a liquid layer to a continuous moving film in the direction in which the film is traveling.

7. A high speed data processing apparatus as in claim 2 wherein said applicator and said barrier means form a unitary structure.

8. A high speed data processing apparatus as in claim 7 further including means for enabling disassembling of said apparatus for ease of maintenance.

9. A high speed data processing apparatus as in claim 8 wherein said barrier means further comprises a smooth sheet which extends itself into the applicator and forms a wall between an inlet fluid holding chamber and an outlet fluid dispensing chamber of said applicator, thereby providing a smooth wall along which the fluid can travel from the applicator to the barrier means.

10. A high speed data processing apparatus as in claim 9 wherein said smooth sheet is composed of stainless steel.

11. A high speed data processing apparatus as in claim 9 wherein said smooth sheet is composed of polytetrafluoroethylene.

12. The combination as set forth in claim 2 wherein said angle of incidence is from about 15 degrees to about 25 degrees.

13. The combination as set forth in claim 3 wherein said angle of incidence is about 15 degrees.

14. A high speed data processing system wherein the data processing apparatus of claim 2 is located above and one same such apparatus is located below a film path to form a pair of data processing units which when in operation exert a substantially equal and opposite pressure against a continuous moving film passing between said units.

15. A high speed data processing system wherein the data processing apparatus of claim 6 is located above and one same such apparatus is located below a film path to form a pair of data processing units which when in operation exert a substantially equal and opposite pressure against a continuous moving film passing between said units.

16. A high speed data processing system as in claim 14 wherein a series of paired data processing units are present thereby forming a film path through which film can be processed.

17. A high speed data processing system as in claim 16 wherein said thin outlet aperture is about $\frac{1}{32}$ inch in width.

18. A high speed data processing system as in claim 16 wherein said barrier means is comprised of a polytetrafluoroethylene smooth surface and wherein said thin outlet aperture is about $\frac{1}{32}$ inch in width.

19. A high speed data processing system as in claim 15 wherein said thin outlet aperture has a width of less than about $\frac{1}{16}$ inch and wherein said angle of incidence is from about 15 degrees to about 25 degrees.
